Atty.

UNITED STATES PATENT OFFICE.

WILLIAM HUGHES, OF TAUNTON, MASSACHUSETTS.

SAFETY SEAL FOR LOCKS.

1,403,604.

Specification of Letters Patent. Patented Jan. 17, 1922.

Application filed May 31, 1921. Serial No. 473,627.

To all whom it may concern:

Be it known that I, WILLIAM HUGHES, a citizen of the United States, residing at Taunton, county of Bristol, State of Massachusetts, have invented a certain new and useful Improvement in Safety Seals for Locks, of which the following is a specification, reference being had therein to the accompanying drawings.

10 The object of the invention is to provide a very simple and cheap safety seal for locks. It is especially intended for application to car doors, but it is also applicable to other doors and to trunks, boxes, cases 15 and the like, in which a staple is employed as a part of the locking means.

The invention will be fully understood from the following description when taken in connection with the accompanying drawings, 20 and the novel features thereof will be pointed out and clearly defined in the claims at the close of this specification.

In the drawings, Fig. 1 is a plan view of a device embodying the invention in its 25 fully straightened-out form, the strap being broken intermediate its ends for the sake of saving space in showing the full length of the strap.

Fig. 2 is a side elevation of the device 30 shown in Fig. 1.

Fig. 3 is a sectional view of the left-hand portion of the device shown in Figs. 1 and 2, after the strap has been bent along the line of perforations to fold over the 35 spring catches down into the socket formed to receive them before the sealing device is applied to the lock.

Fig. 4 shows the device after the right-hand end portion has been bent over to 40 bring the tubular eyelet down into engagement with the spring catches to form the locking and sealing connection.

Fig. 5 is a side elevation of a modified 45 form of device and showing the socket base member on the upper side near the left-hand end and the spring catches on the lower side farther away from the end; that is, the position of the socket and the spring catches are just reversed in position from 50 that shown in Fig. 2.

Fig. 6 is a sectional view showing the 55 left-hand portion of the device of Fig. 5 after the socket base member has been bent around to the under side of the spring catches.

Fig. 7 shows the device as applied to the lock of a car door.

Referring now to the drawings, the sealing device comprises a thin strap of flexible metal which can be slipped through the 60 staple or other loop member of the fastening device of a door or other article, and which can then be bent into loop form so as to bring the two ends together into lapped relation, the two ends being formed 65 with interengaging portions which can be snapped together, the interengaging portions of the two ends being such that after once being engaged they can not be separated without breaking the seal. It also 70 comprises a socket portion integral with the strip, having a closed base, said socket being adapted to receive the spring catches and close the entrance thereto from the under side so as to prevent access to the 75 fingers by a tool to open the seal without breaking some part of the device.

The strap 1 of which the device is composed is preferably made of flexible steel which can be easily bent and which may 80 be relatively soft in the intermediate portion between the two end portions in which are formed the spring catch and socket portions, but which is preferably hardened near the end portions so as to make it more 85 frangible, and therefore more surely broken whenever any one attempts to tamper with the seal.

In the forms shown in Figures 1 to 4 inclusive, near the left-hand end of the 90 strap, as shown in Figures 1 and 2, there is punched out a hole and around the margin of the hole there are stamped out the spring catches 2 which extend upward from the plane of the strap, the said fingers tapering toward each other like the sides of the frustum of a cone. There is also stamped out a socket portion 3 some distance back from the end, that is, nearer the center of the strap than the spring catches 95 2, said socket portion being on the under side of the plane of the strap, that is, on the opposite side from the spring catches 2. This socket portion has a closed bottom and closed sides, being merely a recess of 100 105 suitable size and shape to receive the spring catches 2 when the strap is bent intermediate the spring catches and the socket member to fold over the spring catches.

The strap is preferably formed with a 110

transverse line of perforations 4-4 intermediate between the recess portion 3 and the spring catch portion 2, so as to facilitate the bending and also so as to render 5 the strap more frangible along that line. It should be sufficiently strong, however, so that the strap may be folded over onto itself the first time without breaking, but it should be sufficiently frangible so that if 10 the strap is bent back again to disengage the spring fingers, the strap will break.

The strap may be bent over into the form shown in Figure 3 to engage the spring catches 2 in the recess 3 in advance of its 15 attachment to the lock. In fact it may be placed on the market in this form so as to have it ready for use.

Near the right-hand end, that is, near the opposite end from the end which contains 20 the spring catches and socket member, there is connected with the strap a stud 7. The stud 7 is formed with a post portion 13 terminating at one end in a reduced portion 14, thus forming a shoulder 15 at the junction 25 of the portion of larger diameter with the portion of smaller diameter, and when the said stud is riveted to the strap there will be formed a lip 16 clinched on the under side of the strap 1.

30 The said stud is formed with a flange 9 at the outer end of the portion of larger diameter.

When applied to the lock of a car door, as shown in Figure 7, the strap is slipped 35 through a slot in some part of the locking mechanism, being shown in Figure 7 as being slipped through a slot in the tongue 5 and the plate member 6, and then the strap is bent around so as to bring the flanged stud 40 member 7 down into engagement with the catch fingers 2 and pressed in until the flange 9 snaps past the inner ends of the said catches 2 and snaps into engagement with them, as shown in Figure 4. The closed 45 bottom 8 of the socket member 3 prevents access to the catch fingers with a tool, and thus prevents the possibility of releasing the catch fingers from the flange 9 or otherwise opening the seal. It can only be separated 50 by breaking the strap itself which will serve as a telltale that the seal has been tampered with.

The construction shown in Figures 5 and 6 differs slightly from that shown in Figures 1 to 3 inclusive. In this case the left-hand end portion containing the socket member 10 is bent down midway between the socket member and the spring catch fingers so as to bring the socket member down 60 on the under side of the spring catch fingers, and the tip end portion 18 of the strap will lap onto the under side of the main body of the strap, whereas in the form of device shown in Figures 1 to 4 inclusive, the tip 65 end portion 18 laps over onto the upper face

of the strap 1. The stud 7 is attached to the body of the strap at the other end in the same manner as already described and with reference to the first form of construction.

What I claim is:—

1. A safety seal comprising a strap of flexible metal having near one end a plurality of spring catches struck up from the strap, a socket recess stamped in the strap and having a closed bottom and side walls, 75 said socket and spring catches being integral with the strap and adjacent each other near the same end of the strap but projecting from opposite faces of the plane of the strap and so arranged that the strap may be 80 bent over upon itself midway between said socket and said spring catches and bring said catches into the interior of the said socket and pointing toward the base thereof, and a post projecting from the face of the 85 strap near its other end, said post being formed with a flange head so constructed that when the strap is bent over intermediate the two ends to form a loop the said flange post may be inserted into the opening 90 between the spring catches and the flange thereof may be snapped into engagement with the catches after the catch member has been entered in the socket.

2. A safety seal comprising a strap of 95 flexible metal having near one end a plurality of spring catches struck up from the strap, a socket recess stamped in the strap and having a closed bottom and side walls, 100 said socket and spring catches being formed in adjacent portions of the strap, the strap being bent midway between the said catches and socket and folded upon itself in such manner that the catches are entered in the said socket with the ends of the catches 105 pointing toward the base of the socket, and a post projecting from one face of the strap near its other end, said post being formed with a flange head so constructed that when the strap is bent over intermediate the said 110 post and the said interengaged catches and recess, the said post may be inserted into the opening between the said spring catches and its flange engaged with said catches, and the said interengaged flange and ends of the 115 catches be covered by the bottom and side of said recess.

3. A safety seal comprising a strap of flexible metal having near one end a plurality of spring catches struck up from the 120 strap, a socket recess stamped in the strap and having a closed bottom and side walls, 125 said socket and spring catches being formed in adjacent portions of the strap, the strap being bent midway between the said catches, a socket folded upon itself in such manner that the catches are entered in the said socket with the ends of the catches pointing toward the base of the socket, and a post projecting from one face of the strap near 130

its other end, said post being formed with a flange head so constructed, that, when the strap is bent over intermediate the said post and the said interengaged catches in the re- flange of the post being, when the parts are interlocked for sealing, entirely within the space between the base of the socket and the 10 folded portion of the strap.

cess, the said post may be inserted into the opening between the said spring fingers and its flange engaged with said catches, the

In testimony whereof I affix my signature.

WILLIAM HUGHES.
